UNITED STATES PATENT OFFICE.

CHRISTOPHER SOLBERG, OF MINNEAPOLIS, MINNESOTA.

TIRE-HEATING DEVICE.

SPECIFICATION forming part of Letters Patent No. 737,034, dated August 25, 1903.

Application filed January 15, 1903. Serial No. 139,113. (No model.)

To all whom it may concern:

Be it known that I, CHRISTOPHER SOLBERG, a citizen of the United States, residing at Minneapolis, in the county of Hennepin and State of Minnesota, have invented certain new and useful Improvements in Tire-Heating Devices; and I do hereby declare the following to be a full, clear, and exact description of the invention, such as will enable others skilled in the art to which it appertains to make and use the same.

My present invention relates to tire-heating devices and is in the nature of an improvement on the device disclosed and claimed in my prior patent, No. 692,376, of date February 4, 1902, entitled "Tire-heating device."

The objects of my present invention are to improve in point of efficiency the tire-heating devices disclosed in my said prior patent.

To the above ends the invention consists of the novel devices and combinations of devices hereinafter described, and defined in the claims.

The invention is illustrated in the accompanying drawings, wherein like characters indicate like parts throughout the several views.

Figure 1 is a central vertical section showing the tire-heating device constructed in accordance with my invention. Fig. 2 is a plan view of the device with some parts broken away and others removed. Fig. 3 is a plan view of one of the twyers or burners removed from the device and some parts being sectioned. Fig. 4 is a vertical section on the line $\alpha^4 \alpha^4$ of Fig. 3, and Fig. 5 is a detail in end elevation of one of the tire-supporting brackets.

The numeral 1 indicates a hollow body, which is supported by legs 2, and rising from the central portion of which is a tubular standard 3, communicating therewith and provided at its upper end with an oil tank or reservoir 4. In the lower end of the tubular standard 3 is a valve-seat 5, which is adapted to be opened and closed by a needle-valve 6, the stem of which is passed upward through said standard and through said tank 4 and has screw-threaded engagement with the bearing 7 on the top of said tank and is provided with a hand-wheel 8, by means of which said valve may be operated at will. The lower ends of a ra-

dially-disposed series of tire-supporting arms 9 are pivoted to peripheral lugs 10 of the hollow body 1. Only two of these arms are shown in Fig. 2, the rest thereof being removed. Working on the screw-threaded exterior of the standard 3 is an annular nut 11, having a loosely-mounted non-rotary sleeve-section 12, which is connected by radial links 13 to the intermediate portions of the arms 9.

Extending in the same vertical plane with each arm 9 and directly underlying the same is an oil-tube 14, which at its lower end is connected by a swiveled valve-joint 15 to the outer end of a stub-tube 16, which is bent laterally or offset, as shown in Fig. 2, so as to clear the corresponding lug 10, and is then screwed into the body 1. The inner end of each tubular section 15 communicates with a port 17, leading into the interior of said body 1. The several ports 17 are adapted to be simultaneously opened and closed by a perforated annular ring 18, seated within the said body 1 and having teeth which mesh with a pinion 19, the shaft 20 of which projects upward through the top wall of said body 1 and is provided with a handpiece 21.

The upper and outer end of each oil-tube 14 passes directly through a coöperating hollow head 22, which constitutes the generating-chamber of the twyer. At their sides the heads 22 are provided with trunnions 23, which work freely in slots 24, formed in the pronged free ends 25 of the supporting-arms 85 9. At their inner sides the heads 22 are constructed and provided with an inwardly-diverging entrance-passage 22^a, while on their tops they are provided with a gas-escape passage or perforation 22^b. The delivery ends 90 of the gas-tubes 14 are bent inwardly and downwardly and terminate in discharge-nozzles 26, that stand in position to discharge directly into the diverging passages 22^a of the heads 22. Oil-cups 27, which are opened at 95 their sides adjacent to the heads 22, are suitably secured to the oil-pipes 14 in position to receive oil drippings from the nozzles 26.

On each head 22 is rigidly secured a tire-holder or rest-bracket 28, having laterally-spaced and shouldered rest-lugs 28^a, which are adapted to support the tire just above the perforations 22^b of the heads 22.

Operation: As is evident, by adjusting the

nut 11 vertically the supporting-arms 9 will be simultaneously adjusted so as to throw the rest-brackets 28 and the twyer-heads 22 nearer to or farther from the standard 3, keeping the same, however, always on the line of a circle which is concentric to said standard. In this way the device may be adjusted to tires of different sizes. In my prior patent the gas was generated at the part corresponding to the body 1, but in my present invention the gas is generated at the twyers. In starting the generation of gas oil is dripped into the cups 27 and is lighted in much the same manner as an ordinary gasolene stove. When the generation is once started, the burning gases within the heads 22 will produce sufficient heat to continue the generation of gas in the sections of the oil-tubes 14 which pass through said head. The burning gases, escaping through the perforations 22^a, will be directed onto the tire supported on the rest-lugs 28^a of the brackets 28. As the rest-brackets and the heads of the twyers are adjusted together, they are of course always kept in the proper relation to each other to properly direct the flames on the tire supported by the device.

What I claim, and desire to secure by Letters Patent of the United States, is as follows:

1. In a tire-heating device, the combination

with radial supporting-arms, of hollow heads 30 and tire-seats carried at the free end of said arms, said seats being above said heads, said heads having lateral inlet-passages and vertical outlet-passages, the latter being positioned to direct the flame in vertical line with said tire-seats, and oil-delivery tubes passed vertically through the said hollow heads and provided with discharge-nozzles positioned to discharge into said heads through the lateral inlet-passages thereof, substantially as de- 40

2. In a device of the character described, the combination with hollow heads 22, having diverging inlet-passages 22^a, and discharge-perforations 22^b, of the tire-rests on said heads 45 positioned to support the tire above said perforations 22^b, and the oil-delivery tubes 14, passed through said heads 22 and bent downward and terminating in nozzles 26 positioned to discharge into said inlet-passages 22^a, sub- 50

stantially as described.

In testimony whereof I affix my signature in presence of two witnesses.

CHRISTOPHER SOLBERG.

Witnesses:
